PUSH BUTTON LIGHTER

Fayville A. Trow, Albert Lea, Minn.

Application June 18, 1935, Serial No. 27,201

4 Claims. (Cl. 158—85)

The object of my invention is to provide a stove of the type using gasoline under pressure or the like, which is provided with a plurality of burners and which has a push button lighter, whereby all but the master burner may be conveniently and easily lighted from the master burner.

Another object is to provide such a structure in which a pilot light may be eliminated.

It is my particular object to provide a novel and inexpensive and efficient structure in such a lighter device.

With these and other objects in view, my invention consists in the construction, arrangement and combination of the various parts of my push button lighter, whereby the objects contemplated are attained, as hereinafter more fully set forth, pointed out in my claims, and illustrated in the accompanying drawing, in which:—

Figure 1 is a top or plan view of a burner equipped with a push button lighter embodying my invention, parts being broken away and parts being shown in section.

Figure 2 is a detail, sectional view taken on the line 2—2 of Figure 1.

Figure 3 is a detail, sectional view taken on the line 3—3 of Figure 2; and

Figure 4 is a detail, sectional view taken on the line 4—4 of Figure 2.

I shall first describe in a general way the burner structure. The burner manifold is indicated generally at A, and is of peculiar irregular form, varying according to the number of burners proper with which the stove is equipped and varying with other features of stove construction.

The manifold here illustrated is a hollow one with a transversely extending portion 16. From the manifold portion 16 extend the passages 17, 18, 19, and 20 to four burners with which the stove is provided. Three of the burners are indicated at 17a, 18a, and 20a. The burner 20a is the master burner. The burner connected with the passage 19 is omitted but is like the others.

An intake passage 22 leads to the manifold portion 16 and another passage 23 leads from the manifold portion 16 to the passage 24 to the generator burner 25 of the ordinary saw-kerf type.

Arranged above the generator burner 25 and communicating with the intake passage 22 is a generator 31. Fuel is supplied to the generator 31 and thence to the manifold through a valve

43, which is automatically controlled by means of a thermostat 44.

Valve control rods 63, 64, 65, and 66 and ordinary valves not shown in detail, control the flow of fuel from the fuel manifold to the various burners. A valve 40 controls the flow of fuel from the generator to the manifold.

In Figure 1, I have shown at 70 what may be called the generator burner lighter. It is similar in construction to parts of the push button lighter to be later described, and will be referred to again. It is sufficient for the present to say that this burner lighter 70 is of such construction that when the valve 40 and the valve controlled by rod 63, are opened, and the master burner is lighted, fuel will pass to the generator burner 25 and thence upwardly through the lighter 70, where it will be lighted by the flame from the master burner 20a and flame will then pass down through the lighter 70 to the generator burner for igniting the fuel escaping from the generator burner.

I shall now describe in greater detail the push button lighter structure.

Communicating with the manifold section 16 is a tubular elbow fitting 74, best shown in Figure 2.

At the inner end of the fitting 74 is a valve seat 75 with which coats a disc valve 76 on a stem 77 slidably projecting through the wall of the fitting 74 and then extending toward the front of the stove, and provided at its outer end with a push button head 78.

On the stem 77 spaced from the fitting 74 is a fixed collar 79. A coil spring 80 is arranged on the stem 77 between the collar 79 and the fitting 74 under compression, so that it normally holds the valve 76 tightly seated.

By pressing the head 78 inwardly against the tension of the spring 80, the valve 76 can be opened for allowing fuel vapors to pass from the manifold into and through the fitting 74.

The burner lighter structure now to be described can be assembled as a unit, and set on the upper end of the fitting 74.

This lighter structure includes a sleeve 81, telescopically receiving the upper end of the fitting 74 and having a top 82 spaced above the fitting 74, and provided with a series of small perforations 83.

The tube 84 communicates with the interior of the sleeve 81 near the top thereof and extends slightly downwardly to position close to the generator burner 25.

Similar tubes 85 communicate with the upper interior of the sleeve 81 and extend to the other burners.

The tubes 84 and 85 have in their tops longitudinal narrow slots 86.

The outer end of the tube 84 is closed as at 84a, while the tubes 85 preferably have filter screens 87 at their outer ends. The tube 84 has a downwardly opening, channel-shaped hood 88 receiving the tube 84 between its lower side walls, as shown in Figure 2. The tube 88 is open at its lower end adjacent the generator burner 25. The tubes 85 have substantially similar channel-shaped hoods 89 partially receiving them and partially above them. The hoods 89 are substantially closed at their outer ends as at 90.

Each hood 85 has at its outer end at its top, an opening 91.

On the top of the sleeve 81 is a cap 92 having an annular, downwardly extending flange 92a provided with an internal shoulder 93 resting on the top 83. The flange 92a extends downwardly and forms an apron around the upper part of the sleeve 81. In the flange 92a is a series of notches 94 to receive the ends of the hoods 88-89. The cap 92 is held in place on the sleeve 81 by means of a screw 95 extended through the cap and screwed into the top 82.

The generator lighter 10 shown in Figure 1 is similar in general construction to the lighter members already described, having an interior tube similar to the tubes 84-85, its lower end being closed as in the case of the outer end of the tube 84, and its upper end having a screen as in the tubes 85. The lighter 10 has an outer hood similar to the hood 89.

35 *Operation of push button lighter*

Until the valve 16 is opened, the push button lighter ordinarily performs no particular function. Assuming, however, that the generator burner 25 has been lighted from the master burner in the 40 way heretofore described, then the push button lighter may be used for the purpose for which it is intended. In this connection, it may perhaps be mentioned that the tube 84 and hood 88 could be connected with the master burner instead of the generator burner if that were desired. It might also be mentioned that one reason for lighting the master burner 20a instead of the generator burner in starting the stove is that the burner 20a is conveniently accessible when a dirt 50 tray is in place over the burner, whereas the generator burner is not then readily accessible for lighting.

When it is desired to light any one of the other burners (17a, 18a or 19a) from the burner 25, the 55 operator simply pushes on the head 78 and opens the valve 16 (see Figures 1 and 2). Thereupon gas or fumes from the manifold section 16 pass through the fitting 74 into the sleeve 81 and thence through the various tubes 84-85 to the 60 various burners. Gas escaping from the lower end of the tube 84 is ignited from the flame of the burner 25 and then the flame follows along under the hood 88 which guides the flame along the slot 86 and prevents its blowing away. The flame 65 then passes into the cap 92, and then passes to all of the other burners (17a, 18a and 19a) and if either of the valves controlled by the rods 64, 65 or 66 is open, the fuel escaping from the corresponding burner will be ignited.

70 I have thus provided a rather simple and very efficient structure whereby after the master burner

is lighted and the generator burner is burning, any of the three other burners mentioned may be lighted almost instantaneously and very easily by pushing in on the button or head 78.

It may be mentioned that the sleeve 81 can be 5 simply lifted off the fitting 74 and the assembly including the sleeve 81, cap 92, tubes 84-85 and hoods 88-89 may thus be removed or installed as a unit.

It will be obvious that I have provided a very 10 simple and inexpensive push button lighter, by which any of the other burners of the stove may be conveniently and easily lighted after the master burner has been started.

It will, of course, be understood that the details 15 of the construction and arrangement of the parts of my push button lighter and the materials of which they are made may be varied according to circumstances.

It is my intention to cover by my claims any 20 changes or modifications in the structure, arrangement and combination of the parts which may be reasonably included within the scope of such claims and within the scope of my invention.

I claim as my invention:

1. In a lighter structure, a tubular member 25 having a perforated top, a plurality of tubes communicating with the interior of the member at its sides, having longitudinal slots in their tops, a hood over each tube forming a passage above 30 the slot in such tube, and a structure forming a chamber above the member communicating with the member through said perforations, said chamber being also arranged in communication with said hoods at the ends thereof. 35

2. A lighter structure comprising a downwardly opening sleeve adapted to detachably fit on a fuel conducting member and having a closed perforated top and having a plurality of openings in its side wall, a plurality of fuel conducting 40 tubes with perforated tops supported on said sleeve in communication with the respective last named openings, a cap mounted on said sleeve forming a chamber above the sleeve and having openings in its side wall, hoods over the respective tubes having their ends connected with the respective openings in the wall of the cap, the parts being so connected as to form a unitary structure which may be installed or removed as a 45 unit. 50

3. In a lighter structure, a sleeve open at its lower end and having a perforated top and having openings in its side wall, a plurality of lighter tubes perforated at their tops communicating with the respective openings, a structure forming 55 a chamber above said sleeve communicating with the sleeve through the perforations in the top, and a hood for each tube communicating with the said chamber.

4. In a lighter structure, a sleeve open at its 60 lower end and having a perforated top and having openings in its side wall, a plurality of lighter tubes perforated at their tops communicating with the respective openings, a structure forming a chamber above said sleeve communicating 65 with the sleeve by means of said perforations, and a hood for each tube communicating with the said chamber, said chamber comprising a cap with a flange overhanging the sleeve, and means for fastening the cap to the sleeve. 70

FAYVILLE A. TROW.
